UNITED STATES PATENT OFFICE.

ISAAC FRANCIS, OF FREMONT, NEBRASKA.

DESIGN FOR A BOTTLE-OPENER.

41,178.

Specification for Design.

Patented Feb. 14, 1911.

Application filed November 29, 1910. Serial No. 594,798. Term of patent 14 years.

To all whom it may concern:

Be it known that I, ISAAC FRANCIS, a citizen of the United States, residing at Fremont, in the county of Dodge and State of Nebraska, have invented a new, original, and ornamental Design for a Bottle-Opener, of which the following is a specification, reference being had to the accompanying drawing, forming part thereof.

Figure 1 is a side view of a bottle opener

showing my new design. Fig. 2 is a face view of the same.

I claim:

The ornamental design for a bottle opener, as shown.

ISAAC FRANCIS.
